UNITED STATES PATENT OFFICE.

BENJIMAN BANK, OF PHILADELPHIA, PENNSYLVANIA.

TOBACCO PIPE.

Application filed September 10, 1920. Serial No. 409,359.

To all whom it may concern:

Be it known that I, BENJIMAN BANK, a citizen of the United States, residing at Philadelphia, in the county of Philadelphia and State of Pennsylvania, have invented new and useful Improvements in Tobacco Pipes, of which the following is a specification.

My invention relates to new and useful improvements in tobacco pipes, and has for its object to provide a construction wherein the entire bowl may be made of metal the parts being so combined as to eliminate or reduce to a minimum the likelihood of the same becoming unduly heated.

Another object of the invention is to provide the air chamber about the tobacco receptacle through which a draught of circulation will be created by the heating of the inner walls during the process of smoking.

A still further object of the invention is to provide a novel means for attaching the nipple to the bowl, said nipple having the mouth piece connected therewith.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:

Fig. 1, is a plan view of my pipe constructed in accordance with my invention.

Fig. 2, is a fragmentary sectional view thereof.

In carrying out my invention as here embodied, 2 represents the outside casing or bowl of the pipe stamped, molded or drawn from suitable metal such as brass the exterior of which may be enameled in imitation of wood and within this bowl is set the tobacco receptacle 3.

This tobacco receptacle comprises an inner casing 4 of metal such as aluminum open at its upper end to provide for the insertion of tobacco and this casing has an outwardly projecting flange 5 adapted to rest upon the upper edge of the bowl 2 with a rim 6 depending from the flange and engaging the outer face of the bowl 2 at its

upper open end. The casing 4 has two different diameters so as to form an offset or shoulder 7 adjacent its upper end in which are formed a plurality of holes 8 which act as air outlets as will be hereinafter described. At the lower end of the casing 4 and from the metal forming the same is produced the depending spud 9 having a small central opening 10 therethrough through which is drawn the tobacco smoke from the tobacco contained within the receptacle 3.

About the casing 4 and spaced therefrom is an intermediate casing 11 which is also formed of metal such as brass and the upper end thereof fits over the larger portion of the casing 4 and is fastened thereto in any suitable and well known manner, while the lower end has a hole 12 surrounded by an upstanding collar 13 which fits over the spud 9 and if found desirable may be secured thereto. Because of the difference in size between the small portion of the inner casing 4 and said intermediate casing the major portions of the walls of said casing are spaced apart and form an air chamber 14 therebetween to which air is admitted from the atmosphere through the vent tube 15 which is fastened in one of the walls of the bowl 2 and one of the walls of the intermediate casing 11. When the pipe is in use the heat from the burning tobacco within the tobacco receptacle will heat the casing 4 and raise the temperature of the air within the chamber 14 causing said air to pass upward and out through the holes 8 and cause fresh cool air to pass into said chamber through the vent tube 15 which will maintain the inner casing at a relatively low even temperature and prevent or reduce to a minimum the likelihood of the heat passing to other parts of the pipe. The intermediate casing 11 within the plates is spaced from the walls of the pipe bowl as shown in the drawing to provide a chamber about the intermediate casing.

The stem 16 which is formed integral with the bowl 2 is slightly constricted at its end as indicated at 17 and in this constricted end is mounted the nipple 18 which snugly fits in said stem and is held against outward displacement by the ferrule 19 which has a flange 20 for engaging the outer end of the nipple, said ferrule being of such thickness as to lie within the depression formed by the difference in size between the main portion of the stem 16 and

its constricted portion. The nipple has a threaded projection 21 formed therewith to which is detachably fastened the mouth piece 22 in the ordinary well known manner, said mouth piece having a hole 23 therethrough which registers with a hole 24 through the nipple and its projection.

The walls of the different elements making up the pipe being formed of relatively thin metal large air spaces are provided between the different parts which not only help to maintain the pipe in a cool condition, but also assists in cooling the smoke before reaching the mouth of the user which is quite advantageous.

When the pipe is in use the smoke will be drawn down through the hole 10 in the spud 9 and into the bowl where it will circulate about the intermediate casing 11 and reduce in temperature as it passes off through the stem and mouth piece and as before stated both the inner and intermediate casings 4 and 11 will be maintained relatively cool by the circulation of air through the vent tube 15 and the chamber 14.

The large chamber in the bowl and its stem form a receptacle for any fine pieces of tobacco, ashes or juices that may fall from the tobacco receptacle through the hole 12 and as the hole or passageway 24 through the nipple is considerably removed from the walls of the stem 16 these pieces of tobacco or other foreign matter will not be drawn into the smoker's mouth but will be retained until the tobacco receptacle, including the inner and outer casings, is removed and matter in the bowl dislodged. The tobacco receptacle being removable, if it should be injured or broken it may be readily replaced by a new one.

Of course I do not wish to be limited to

the exact details of construction as herein shown as these may be varied within the limits of the appended claims without departing from the spirit of my invention.

Having thus fully described by invention, what I claim as new and useful is:

1. A pipe comprising a metallic bowl, a metallic inner casing supported by said bowl within the same, said casing having an opening at its lower end and a plurality of holes adjacent its upper end, an intermediate casing surrounding said inner casing and spaced therefrom to form an air chamber, and a vent tube passing through the walls of said intermediate chamber and the pipe bowl to form a communication for the air chamber with the atmosphere.

2. A pipe including a bowl, an inner casing supported within said bowl and an intermediate casing fixed to the inner casing and spaced therefrom throughout portions thereof to form an air chamber, said inner casing having direct draught communication with the pipe bowl and said air chamber having an inlet and an outlet leading directly from and to the atmosphere independent of the pipe draught.

3. A tobacco pipe including a bowl providing a chamber, an inner casing suspended within said bowl and providing a tobacco chamber in direct communication with the bowl chamber and an intermediate casing surrounding the inner casing within the bowl and spaced from the walls of said inner casing and bowl to provide an intermediate air chamber for communication with the atmosphere at two separated points.

In testimony whereof, I have hereunto affixed my signature.

BENJIMAN BANK.
